[57] ABSTRACT

A shirt with a "built in" collar is provided. The shirt may be prepared from either one or two sections of fabric. In either case the neck collar portion of the fabric is specifically cut so that upon assembly of the shirt a full collar portion thereof may be formed by simply folding back the fabric around edges of the neck opening.

SHIRT FABRICATION

DESCRIPTION OF THE INVENTION

The present invention relates generally to garment manufacture and, more particularly, to an improved shirt having an integral collar and a method of fabricating the same.

It is a primary object of this invention to provide an improved shirt having an integral collar that can be easily and economically fabricated.

A more particular object of the invention is to provide such an improved shirt that can be fabricated from only one or two sections or panels of fabric.

It is another object of the present invention to provide a method for producing such an improved shirt.

It is yet another object of the present invention to provide such a method which permits the manufacture of such shirts in both an economical and efficient manner.

Other objects and advantages of the invention will become apparent upon reading the following detailed description and upon reference to the drawings in which:

FIG. 1 is a perspective view of the finished fabricated shirt with a V-line collar prepared in accordance with the teachings of this invention.

FIG. 2 is a perspective view of front and back panels used to form the shirt shown in FIG. 1.

FIG. 3, 4 and 5 are front elevations of single fabric panels each of which may be folded and cut to form a shirt embodying the invention.

FIG. 6 is a front elevation of a cut front panel of a V-line collar shirt to be fabricated in accordance with the teachings of this invention.

FIG. 7 is a front elevation of a V-line collar fabricated in accordance with the teachings of this invention.

FIG. 8 is a front schematic elevation of a one-half V-line collar lying on a X-Y coordinate system used to define the mathematical relationships existing between the various lines which define the collar.

FIG. 9 is a perspective view of the finished fabricated shirt with a U-line collar prepared in accordance with the teachings of this invention.

While the invention will be described in connection with certain preferred embodiments, it will be understood that I do not intend to limit the invention to these particular embodiments. On the contrary, I intend to cover all alternatives, modifications, and equivalents as may be included within the spirit and scope of the invention.

The term "shirt" as used herein is intended to include virtually any garment worn to cover the upper part of the body and which includes a main body portion, right and left sleeves, a collar and proper openings for neck, arms and lower trunk, including garments such as robes, dresses, kimonos and similar articles.

For convenience the term "sleeve" is used herein throughout to refer to a part of the shirt extending from the arm's eye. The length of the sleeve may vary to cover part or all of an arm, so that the term "shirt" includes a sleeveless shirt, in which the arm's eye and the sleeve opening are the same.

Turning now to the drawings, and referring first to FIGS. 1 and 2, there is shown a shirt 10 made from two panels 11 and 12 referred to as front and rear panels, respectively.

Each panel 11 and 12 is cut generally in the shape of a human torso bounded by left and right peripheral shoulder boundaries 13b, 13d and 13a, 13c, left and right sleeve portions 11b, 12b and 11a, 12a bounded by top and bottom peripheral sleeve boundaries 11at-12at, 11ab-12ab and 11bt-12bt, 11bb-12bb, left and right side portion boundaries 15b, 15d and 15a, 15c, lower trunk opening boundary portions 16a and 16b and front and back neck or collar opening boundary portions 14a and 14b respectively.

In fabricating the illustrative shirt of FIG. 1, the front and back panels are attached to one another along the peripheral shoulder boundaries 13a, 13c and 13b, 13d, side portion boundaries 15a, 15c and 15b, 15d, and top and bottom peripheral

sleeve boundaries 11at-12at, 11ab-12ab and 11bt-12bt, 11bb-12bb of sleeve portions 11b, 12b and 11a, 12a.

FIGS. 3, 4, 5, illustrate single panels of material which may be folded and cut to form a shirt embodying the invention.

5 The actual physical attachment of the panels may be effected via sewing means, adhesive means or other fastening means. It should be noted that if a sewing means is employed, very simple stitch operations are involved.

In accordance with one important aspect of the invention 10 the neck collar portion of the front panel is cut such that a smooth, full, continuous V-collar-line is formed upon proper inversion and subsequent folding. The front panel may be cut prior or subsequent to interconnecting the front and rear panels. However in most cases it is preferably cut prior to interconnection.

In order to form a V-line collar it is necessary to properly 15 cut the front panel of the shirt to be fabricated. To determine how the front panel of the shirt is to be cut, it is first necessary to determine a reference point, O, which lies on an approximate longitudinal centerline. The longitudinal centerline divides the front panel into left and right areas. The front panel is then cut along left and right area cut lines, each cut line being maintained within its respective left and right area and extending from O to points A_L and A_R respectively. In a preferred embodiment the left and right area cuts are mirror images of one another. Both A_L and A_R are equidistant from O. However O cannot lie on a line determined by connecting A_L and A_R.

20 25 30 A_L is the point at which the left peripheral shoulder boundary of the panel intersects the neck opening portion. Similar A_R is the point at which the right peripheral shoulder boundary of the panel intersects the neck opening portion.

Upon making such cuts a V-shape neck opening portion is 35 formed. The integral collar is then formed by inverting the V-shape neck opening portion about inversion points D_L and D_R each lying about equidistantly from O.

D_L lies on the left peripheral shoulder boundary. D_R lies on the 40 right peripheral shoulder boundaries. D_L and D_R are spaced away from A_L and A_R respectively. Upon inverting the V-shape neck opening portion about these points and subsequently folding the resulting collar in place a full, continuous collar is formed.

45 In a preferred embodiment of my invention inversions points D_L and D_R include all points from B_L to A_L and from points B_R to A_R respectively. B_L and B_R are points lying on the left and right peripheral shoulder boundaries respectively.

In order to define the location of the points lying from B_L to 50 55 A_L and B_R to A_R it is noted that upon inverting and folding the resulting collar portion about points B_L and B_R, the sum of the distances between coplanar points O-F_L, and F_L-A_L is equal to the distance between coplanar points O-A_L while in the unfolded, uninverted position. Similarly when in the folded, inverted position, the total sum of the distances between coplanar points O-F_R and F_R-A_R is equal to the distance between coplanar points O-A_R while in the uninverted, unfolded position.

F_L is a point determined by the intersection of the left 60 65 peripheral shoulder boundary with a line in the inverted, folded position which when said line is in the uninverted, unfolded position, it lies on a line formed by joining points O and A_L. Similarly F_R is a point determined by the intersection of the right peripheral shoulder boundary and a line in the inverted, folded position which when said line is in the uninverted, unfolded position, it lies on a line formed by joining O and A_R.

Alternatively, cuts may be made on the front panels such that a U-collar-line is produced.

70 75 Once again an approximate center line divides the front panel into left and right areas. A left and a right reference point, O_L and O_R respectively, are determined. Each reference point is equidistant from the approximate horizontal centerline. Also, each reference point lies on a line perpendicular to the approximate longitudinal centerline. The location of the

perpendicular line is restricted in that it cannot lie on the peripheral neck opening boundary line portion of the rear panel.

The front panel is cut along left and right area cut lines. Each cut line is maintained within its respective left and right area and extends from O_L and O_R to points A_L and A_R respectively. Preferably, such cut lines are mirror images of one another.

A_L may be identified by noting that it is a point at which the left peripheral shoulder boundary intersects the neck opening portion. Similarly A_R is a point at which the right peripheral shoulder boundary intersects the neck opening portion. Upon cutting to the respective points, a U-shape collar is formed.

The full continuous built in collar is formed by inverting and folding the U-shape neck opening portion about inversion points D_L and D_R .

Point D_L lies on the left peripheral shoulder boundary and point D_R lies on the right peripheral shoulder boundary. D_L and D_R are spaced away from A_L and A_R respectively.

The distances between O_L-D_L and O_R-D_R are about equal.

Preferably the inversion points D_L and D_R include all points from B_L to A_L and from points B_R to A_R respectively. B_L and B_R are points lying on the left and right peripheral shoulder boundaries respectively.

In order to define the location of the points lying from B_L to A_L and from B_R to A_R it is noted that upon inverting and subsequently folding the U-shape neck portion about points B_L and B_R , the sum of the distances between coplanar points O_L-F_L and F_L-A_L is equal to the distance between coplanar points O_L-A_L while in the unfolded, uninverted position. Similarly, when in the folded, inverted position, the sum of the distances between coplanar points O_R-F_R and F_R-A_R is equal to the distance between coplanar points O_R-A_R while in the unfolded, uninverted position.

F_L is a point determined by the intersection of the left peripheral shoulder boundary with a line in the inverted, folded position which when said line is in the uninverted unfolded position, it lies on a line formed by joining O_L-A_L .

F_R is determined by the intersection of the right peripheral shoulder boundary with a line in the inverted position which when said line is in the uninverted unfolded position it lies on a line formed by joining O_R-A_R .

In the most preferred embodiment of this invention the inversion points are B_L and B_R .

In order to demonstrate the teachings of my invention in producing a V-line collar shirt, reference is made to FIGS. 6 and 7.

FIG. 6 shows a front elevation of the shirt to be collared in accordance with the teachings of this invention. FIG. 7 shows the formed collar of the shirt in FIG. 6.

With regard to FIG. 6, the illustrated front panel comprises two sleeve portions 1 and 2 and a main body portion 3. Lines 4-5 and 6-7 represent imaginary armscye boundary lines which separate the shoulder portions 8 and 9 respectively from the sleeve portion 10 and 11 respectively. Points A_R and A_L are the points joining the peripheral left shoulder boundary and the peripheral right shoulder boundary to the neck opening portion 12.

Points A_L and A_R are about equidistant from a reference point O which lies on an approximate longitudinal centerline d , d' . Center line d , d' , divides the front panel into left and right areas. However, it should be noted that point O cannot lie on the neck opening portion 12.

The front panel is cut along left and right cut lines 14 and 15 respectively. Each cut line must be maintained within its respective left and right area. The cut lines extend from reference point O to points A_L and A_R . The cuts may be of any design but are preferably mirror images of one another. The simplest form for said cut lines would be straight lines formed by joining reference point O and points A_L and A_R respectively. For purposes of illustrating my invention I have chosen to employ simple straight cut lines.

In order to form the collar taught by my invention it is necessary to invert the V-shape neck opening portion about two inversion points D_L and D_R , each lying on the respective left and right peripheral shoulder boundaries. Also, points D_L and D_R may not include points A_L or A_R respectively. The V-shape neck opening portion which is inverted comprises the front pattern fabric material surrounding the V neck opening.

In a preferred embodiment of my invention, the inversion points are limited. In such an embodiment inversion points D_L and D_R must include all points from B_L to A_L , and from B_R and A_R respectively.

Points B_L and B_R are points lying on the left and right peripheral shoulder boundaries respectively. Upon inverting and folding the V neck opening portion about inversion points B_L and B_R , a collar as shown in FIG. 7 is produced. The collar as such will be referred to as being in the inverted, folded position. While in this inverted and folded position the sum of the straight linear distances between points $O-F_L$ and F_L-A_L , all lying within the same plane, is equal to the distance between points $O-A_L$ when the collar is in the uninverted, unfolded position. Similarly the sum of the straight linear distances between points $O-F_R$ and F_R-A_R , in the inverted, folded position and lying in the same plane, is equal to the distance between points O and A_R in the uninverted, unfolded position.

In the most preferred embodiment of the invention the inversion points are points B_L and B_R as defined above. Such is the case for it is only with these points that a collar will be produced which is full, continuous, wrinkle and ripple free, and which does not tend to pull upon formation. From an empirical point of view, it can be noted that if the sum of the distances between point $O-F_L$ and F_L-A_L in the inverted, folded position is greater than the distance between points $O-A_L$ in the uninverted, unfolded position and if the sum of the distances between points $O-F_R$ and F_R-A_R in the inverted, folded position is greater than the distance between points $O-A_R$ in the uninverted, unfolded position, the collar will tend to pull the fabric of the shirt until such distances are equal since there is an insufficient amount of fabric to extend from O to A_L and O to A_R in the inverted folded position. Such an effect will cause a very poor-looking discontinuous, highly wrinkled collar. Similarly, if the distance between points $O-F_L$ and F_L-A_L , in the inverted, folded position, is less than the distance between points $O-A_L$ in the uninverted, unfolded position and if the sum of the distances between points $O-F_R$ and F_R-A_R in the inverted folded position is less than the distance between points $O-A_R$ in the uninverted, unfolded position, the collar will tend to ripple since there is an excess amount of fabric between $O-A_L$ and $O-A_R$, while in the inverted, folded position. A rippled collar is not however as unattractive as the wrinkled collar.

The two variables affecting the determination of the critical inversion points are the length of the neck opening portion of the shirt in the uninverted, unfolded position and the slope of the left and right shoulder boundaries.

For the purpose of mathematically determining the location of the critical inversion points, reference is made to FIG. 8 where there is given on an X-Y coordinate system the various peripheral boundaries defining one-half of the symmetrical V-shape collar shown in FIGS. 6 and 7.

The reference point O is given at the origin. Triangle OAA_L represents the front panel collar boundary as originally cut in the uninverted, unfolded position where the distance between A_L and A is one-half the length of the neck opening portion defined as C which would be known for a given shirt. Also, the y coordinate of point A would be known. Line 17 represents the peripheral left shoulder boundary upon which the most preferred inversion point B_L may be found. Triangle OBB_L represents the inside boundaries of the formed collar. Four-sided figure OGA_LF_L represents the outside boundaries of the formed collar. It should be noted that point A_L is given in both the inverted, folded position and in the uninverted, unfolded position. The distance between points A and G will be defined to equal f . The angle θ , which is known for a given

shirt, is defined to be the angle between lines $\overline{OA}$ and $\overline{OA_L}$. Coordinates x_1, y_1 at F_L define the point at which $\overline{OA_L}$ intersects the left peripheral shoulder boundary 17 when in the inverted, folded position.

In order to establish the location of x_1 and y_1 , three equations must be solved simultaneously. Since any one shirt may be cut differently from another the equations must be given in general form. The three equations are:

I $y_1 = F(x_1)$ 10

II $0.5\theta = \text{arc tan} \frac{H(f)}{1-\frac{1}{2}} - 0.5 \text{arc tan} \frac{x_1}{y_1}$

III $(x_1^2 + y_1^2)^{1/2} + [(x_1 - C)^2 + (y_1 - [1-f])^2]^{1/2} = \frac{C}{\sin \theta}$ 15

Equation I is derived from the known equation of the line corresponding to the peripheral shoulder boundary for a given shirt which may be generally written as

(a) $y = F(x)$

Equation II represents the relationship between f and y_1 and x_1 . It may be derived by noting that the angle 2α is the angle between $\overline{OA_L}$ and $\overline{OF_L}$. Inversion point B_L must lie on a line passing through O which bisects angle 2α . Therefore the angle between $\overline{OA_L}$ and $\overline{OB_L}$ is α ; the angle between $\overline{OB_L}$ and $\overline{OF_L}$ is also α ; the angle between $\overline{OA}$ and $\overline{OB_L}$ is $(\theta + \alpha)$; and the angle between $\overline{OA}$ and $\overline{OF_L}$ is $(\theta + 2\alpha)$. Consequently,

(b) $\tan(\theta + \alpha) = x_1/y_1$ 30

(c) $\tan(\theta + 2\alpha) = x_1/y_1$

Coordinate points x_2 and y_2 of point B_L also lie on the line corresponding to the peripheral shoulder boundary and may therefore be written as

(d) $y_2 = F(x_2)$ 35

Equation (d) may be rewritten such that x_2 is a function of y_2 as follows:

(e) $x_2 = G(y_2)$

It is also known that

(f) $y_2 = 1 - (f/2)$ 40

Therefore since y_2 is a function of f , equation (e) may be written in terms such that x_2 is a function of f or

(g) $x_2 = H(f)$

The following equation results upon substituting equations (f) and (g) into equation (b) 45

(h) $\tan(\theta + \alpha) = \frac{H(f)}{1 - \frac{f}{2}}$

The following equations then result upon taking the arc tan of equations (c) and (h): 50

(i) $\theta + 2\alpha = \text{arc tan} \frac{x_1}{y_1}$ 55

(j) $\theta + \alpha = \text{arc tan} \frac{H(f)}{1 - \frac{f}{2}}$

Multiplying equation (i) by a negative 0.5 and adding the result to equation (j), there results equation II or 60

$0.5\theta = \text{arc tan} \frac{H(f)}{1 - \frac{f}{2}} - 0.5 \text{arc tan} \frac{x_1}{y_1}$

Equation (III) defines the relationship which must exist between points in the inverted and uninverted position necessary to obtain a wrinkle-free, ripple-free, full, continuous collar. It should be noted that all the defined points exist in the same plane. Equation (III) shows $\overline{OF_L} + \overline{F_L A_L}$, i.e.,

$(x^2 + y^2)^{1/2}[(x - C)^2 + (y - [1 - f])^2]^{1/2}$

is equal to $\overline{OA_L}$, i.e., $C/\sin \theta$.

Since there are three unknowns, i.e., x_1, y_1 and f and three equations, f, x_1 and y_1 may be determined by the simultaneous 75

solution of the equations. Upon determining f , points x_2 and y_2 may then be determined by the other functional relationships, i.e., equations (f) and (g).

By following the above mathematical determinations, the 5 location of the most preferred inversion points, B_L and B_R may always be established. The mathematical manipulations as shown are not meant to be in any way restrictive, since many other combinations of the above relationship may be used to establish the location of said preferred inversion points.

In constructing the U-shape it should be appreciated that relationships identical to those described for the V-shape collar exist. There is one important qualification to such a statement. The relationships exist with respect to two individual center reference points.

It should also be noted that informing either the V- or U-shape collar the distance between A_L and A_R , i.e., the neck opening portion, is preferably that of normal shirt neck sizes.

Upon forming a U-shaped collar in accordance with the teachings of my invention a product illustrated by the perspective view given in FIG. 9 results.

By practicing my invention it is possible to fabricate a shirt with an integral of "built in" collar from only one or two panels of fabric. I am able to do this as a result of specifically cutting the front panel of the shirt to be fabricated in accordance with the teachings of this invention.

Any type of woven or nonwoven synthetic or nonsynthetic which is adaptable to manufacture wearing apparel may be used as a fabric of my invention. However my invention is particularly useful with disposable fabrics.

I claim as my invention:

1. A method or fabricating a V-line collared shirt comprising the steps of:

A. cutting front and rear panels of a shirt in the form of a human torso from a fabric bounded by left and right peripheral shoulder boundaries, left and right sleeve portions where said sleeve portions are bounded by top and bottom peripheral sleeve boundaries and arm opening portions, left and right side boundary portions, lower trunk opening boundary portions and neck opening boundary portions;

B. determining a reference point O , which lies on an approximate longitudinal centerline, which divides said front panel into left and right areas;

C. cutting said front panel along left and right cut lines, each cut line being maintained within its respective area and extending from O to points A_L and A_R , respectively, said points also being equidistant from O and where point A_L is the point at which the left peripheral shoulder boundary intersects the neck opening portion and where point A_R is the point at which the right peripheral shoulder boundary intersects the neck opening portion, such that a V-shape neck opening portion is formed;

D. attaching said front and back panels to one another along said peripheral shoulder boundaries, said side portion boundaries and said top and bottom peripheral sleeve boundaries; and

E. forming a collar by inverting the V-shape neck opening portion about inversion points D_L and D_R each lying about equidistantly from O and where point D_L lies on the left peripheral shoulder boundary spaced away from point A_L and point D_R lies on the right peripheral shoulder boundary spaced away from point A_R such that a collar is formed.

2. The method of claim 1 where inversion point D_L includes all points from B_L to A_L and inversion point D_R includes all points from B_R to A_R where

points B_L and B_R are points lying on the left and right peripheral shoulder boundaries respectively such that upon inverting and folding the V-shape neck opening portion about points B_L and B_R

the sum of the distances between folded, inverted positioned, coplanar points $O - F_L$ and $F_L - A_L$ is equal to the distance between coplanar points $O - A_L$ when in the unfolded, uninverted position and

similarly, the sum of the distances between folded inverted positioned coplanar points $O-F_L$ and F_R-A_R is equal to the distance between coplanar points $O-A_R$ when in the unfolded, uninverted position and where F_L is a point determined by the intersection of the left peripheral shoulder boundary with a line in the inverted position which when said line is in the uninverted unfolded position lies on a line formed by joining points $O-A_L$ and similarly where F_R is a point determined by the intersection of the right peripheral shoulder boundary with a line in the inverted position which when said line is in the uninverted, unfolded position lies on a line formed by joining points $O-A_R$.

3. The method of claim 2 where the inversion points are B_L and B_R .

4. The method of claim 1 where the left and right cut lines are mirror images of one another.

5. A method for fabricating a U-line collared shirt comprising the steps of:

A. cutting front and rear panels of a shirt in the form of a human torso from a fabric bounded by left and right peripheral shoulder boundaries, left and right sleeve portions where said sleeve portions are bounded by top and bottom peripheral sleeve boundaries and arm opening portions, left and right side boundary portions, lower trunk opening boundary portions and neck opening boundary portions;

B. determining left and right reference points O_L and O_R respectively each being equidistant from an approximate longitudinal centerline, which divides said front panel into left and right areas, and which lie on a line approximately perpendicular to said longitudinal centerline;

C. cutting said front panel along left and right cut lines, each cut line being maintained within its respective area and extending from O_L and O_R to points A_L and A_R , respectively, said points being equidistant from points O_L and O_R respectively and where A_L is the point at which the left peripheral shoulder boundary intersects the neck opening boundary portion and A_R is the point at which the right peripheral shoulder boundary intersects the neck opening

portion such that a U-shape collar is formed; D. attaching said front and back panels to one another along said peripheral shoulder boundaries, said side portion boundaries and said top and bottom peripheral sleeve boundaries; and

E. forming a collar by inverting the U-shape neck opening portion about inversion points D_L and D_R where point D_L lies on the left peripheral shoulder boundary spaced away from point A_L and point D_R lies on the right peripheral shoulder boundary spaced away from point A_R such that distances between O_L to D_L and O_R to D_R are about equal and a collar is formed.

6. The method of claim 5 where inversion point D_L includes all points from B_L to A_L and inversion point D_R includes all points from B_R to A_R where

points B_L and B_R are points lying on the left and right peripheral shoulder boundaries respectively such that upon inverting and folding the U-shape neck opening portion about points B_L and B_R

the sum of the distances between folded, inverted positioned, coplanar points O_L-F_L and F_L-A_L is equal to the distance between coplanar points O_R-A_R when in the unfolded, uninverted position and similarly, the sum of the distances between folded inverted positioned coplanar points O_R-F_R and F_R-A_R is equal to the distance between coplanar points O_R-A_R when in the unfolded, uninverted position;

where F_L is a point determined by the intersection of the left peripheral shoulder boundary with a line in the inverted position which when said portion is in the uninverted, unfolded position lies on a line formed by joining points O_L-A_L and

similarly where F_R is a point determined by the intersection of the right peripheral shoulder boundary with a line in the inverted position which when said line is in the uninverted, unfolded position lies on a line formed by joining points O_R-A_R .

7. The method of claim 6 where the inversion points are B_L and B_R .

8. The method of claim 5 where the right and left area cuts are mirror images of one another.
